CLAIM

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of an electronic device with graphical user interface, showing a first embodiment of the claimed design;

FIG. 2 is a second embodiment thereof;

FIG. 3 is a third embodiment thereof;

FIG. 4 is a fourth embodiment thereof;

FIG. 5 is a fifth embodiment thereof;

FIG. 6 is a sixth embodiment thereof;

FIG. 7 is a seventh embodiment thereof;

FIG. 8 is an eighth embodiment thereof; and,

FIG. 9 is a front view of an alternative electronic device with graphical user interface, showing the first embodiment of the claimed design. Embodiments 2-8 may be applied to the alternative electronic device.

The broken lines in the figures show an electronic device FIGS. 1-8 and an alternative electronic device in FIG. 9, and form no part of the claimed design.
